UNITED STATES PATENT OFFICE.

ISAAC CRUZAN, OF DECATUR, ILLINOIS.

END-GATE.

SPECIFICATION forming part of Letters Patent No. 601,433, dated March 29, 1898.

Application filed June 29, 1897. Serial No. 642,835. (No model.)

To all whom it may concern:

Be it known that I, ISAAC CRUZAN, a citizen of the United States, residing at Decatur, in the county of Macon and State of Illinois, 5 have invented a new and useful End-Gate, of which the following is a specification.

My invention relates to improvements in end-gates to be used as a shoveling-board as well as a closure for a wagon-body; and the 10 object of my present improvement is to construct the various parts in the simplest possible manner consistent with strength, durability, and wear of the several elements, thereby enabling me to produce a structure which 15 can be manufactured and sold at a low figure.

With these ends in view my invention consists in the peculiar construction, arrangement, and adaptation of parts, which will be hereinafter fully described, and particularly 20 pointed out in the claims.

To enable others to understand my invention, I have illustrated the preferred embodiment thereof in the accompanying drawings, forming a part of this specification, and in 25 which—

Figure 1 is a perspective view of my end-gate, showing it closed and locked against the rear end of a wagon-body. Fig. 2 is a side elevation with the end-gate lowered to show 30 it adapted for service as a shoveling-board. Fig. 3 is a detail sectional view through the end-gate to show the manner of uniting the wings thereto, the plane of the section being indicated by the dotted line 3 3 of Fig. 1; 35 Fig. 4, a detail view of the locking-catch. Fig. 5 is a detail view of one of the clips or brackets upon which the end-gate may rest when turned to an upright position. Fig. 6 is a detail view of the bracket-plate.

Like numerals of reference denote corresponding parts in all the figures of the drawings, referring to which—

I designates my improved end-gate. The gate proper is made of wood, and it is provided at its side edges with the tapering wings 2 2, which are made of metal, preferably sheet-steel. The wings are flanged at their straight edges, as indicated at 3 3, and the wings are applied laterally to the edges 45 of the gate 1 to have their flanges 3 3 overlap the gate. Across the outside of the gate and the overlapping flanges of the wings are ar-

ranged the cleats 4, that bear upon the gate and the flanged wings, and the parts are substantially and securely united together by the 55 bolts 5, that pass through the cleats, the flanges of the wings, and the gate. This construction is very simple and produces a gate which is strong and durable in service.

An ordinary wagon-body, such as is in every-day use extensively throughout the country, is indicated at 7 in the drawings. Such a wagon-body is usually constructed with an outside horizontal cleat 8, which is fastened to the lower side at the rear edge of the bottom of the wagon-body, and said cleat 8 is extended at its ends beyond the side walls of the wagon-body, as at 9. The wagon-body is also provided with inside parallel cleats 10, which are attached to the walls or sides of 70 said body at its open rear end.

I construct my end-gate to utilize the projecting ends 9 of the bottom cleat as bearings for the wings of the end-gate. To this end the wide end of each wing is cut away from 75 the flanged edge to a suitable distance near the inclined edge of said wing to provide the notch 11 and to make a projecting tongue 12 on the broad end of the wing, and the metal of the cut-away or notched part of the wing is doubled or folded upon the tongue 12 to provide 80 the reinforcement 13, that serves to make the tongue strong, prevent it from bending, and to serve as a bearing for the tongue when the gate is turned to its upright position, because 85 said reinforcement or doubled edge of the tongue is brought to bear against the front edge of the projecting end 9 of the bottom cleat 8. As the cleat 8 is of wood, it is liable to become worn by the edges of the metallic 90 wing bearing thereon, and to obviate this I apply metallic wear-plates 14 to the extended ends 9 of the cleat. These wear-plates are flanged or of angular form to embrace the top and front face of the end 9 of the wood cleat, 95 and said plates are fastened in place by a staple or a bolt.

To the rear edge of the bottom of the wagon-body are attached the brackets or keepers 15, upon which the end-gate 1 rests and by which 100 its inner or lower edge is held in position when the gate is lowered. These brackets each consist of an angular piece of metal flanged to fit against the edge of the bottom of the wagon-

body, to which said bracket or keeper is attached by screws or bolts. The brackets extend outwardly to form good supports for the lower edge of the end-gate, and said brackets have upwardly-extending flanges to embrace the metallic wings of the end-gate when the gate is turned to a vertical position to cause the notched edges of the wings to rest upon the projecting ends 9 of the bottom cleat 8.

10 Near the sides of the end-gate, at points between the top and bottom edges thereof, are produced the holes 17, which coincide with similar holes 19, formed in the flanges 3 of the wings 2. Through these holes 17 19 in the end-gate and its wings pass the holding and locking rods 20. These rods are provided at their outer ends with the angular bent nibs 21, and the inner ends of said rods are formed into hooks or eyes, which are loosely connected to the holding-straps 23. These holding-straps are applied to the outside of the walls of the wagon-body, to which they are fastened by suitable bolts or screws. The holding-straps have their rear ends extended beyond the rear edge of the wagon-body, and said extended ends of the straps are bent to form the angular flange that laps the rear edge of the body. The rear projecting extremity of the holding-strap has an eye or aperture 30 into which is loosely fitted the hook or eye on the forward end of the holding-rod.

The rear bent ends of the holding-straps are adapted to pass through the openings 17 19 in the gate and its wings when the gate is turned to a vertical position against the wagon-body, and the rods 20 are intended to be folded or turned inwardly across the outside of the gate to be held in place by a locking-catch 25, which is attached to the middle 40 of the gate.

As the edges of the openings 17 19 in the gate and its wings are exposed to considerable wear, due to the pressure thereon of the holding-rods when they are turned across the gate, I provide the heavy wear-plates 24, which are fitted over the flanges of the wings and which are themselves flanged to embrace the outside of the wings, said wear-plates being held securely in place by bolts, as shown. 45 Each wear-plate fits over the gate and the flanged wing where the openings are produced therein; and the wear-plate itself has an opening 24', which coincides with the openings 17 19, and the edge of the wear-plate is thus presented as a bearing or fulcrum for the locking-rod when the latter is turned crosswise on the gate to be engaged with the catch. This catch 25 is of novel construction, designed to securely hold the inner ends 50 of the rods in secure engagement therewith and to enable the operator to adjust said catch to easily and quickly release the same from the rods. The catch consists of an elongated shank bent at an intermediate point of its length, and one end of this shank is fastened to the gate 1 by bolts or screws. The shank is designated at 26, and to the free end

thereof, which stands off from the face of the end-gate, is attached a spring 27. This spring is of the kind known as a "leaf-spring," and it 70 is normally inclined away from the offstanding free end of the shank, so as to project toward the gate 1, thus closing the space or throat between the offstanding end of the shank and the gate. In the shank is formed 75 a transverse aperture 28, through which passes the operating-spindle 29, the inner end of which is rigidly attached to the free end of the spring 27, while the outer end of said spindle is provided with a suitable head 30, 80 adapted to afford a convenient means to the operator in retracting the spring 27 to permit the rods to be withdrawn from engagement with the catch.

When the gate is turned to a vertical position against the wagon-body, the projecting angular ends of the holding-straps pass through the openings in the gate, its flanged wings, and the wear-plates. The rods 20 are now turned across the gate to bear upon the 90 wear-plates 24, and the inner ends of said rods may be snapped into engagement with the catch 25, the spring 27 of which yields to permit the inner ends of the rods to pass below said spring. The rods are thus held 95 by the catch to hold the gate in its locked position; but to lower the gate the operator pulls on the spindle 29 to retract the spring 27, then lifts the rods out of the catch, and turns the rods to positions substantially in 100 alignment with the holding-straps, whereby the gate may be lowered until its movement is arrested by the nibs or angular ends on the rods, the latter serving to hold the gate in its lowered position convenient for the removal 105 of the contents of the wagon.

Various slight changes in the form and proportion of parts and in the details of construction may be made without departing from my invention.

Having thus fully described my invention, what I claim as new, and desire to secure by Letters Patent, is—

1. The combination with an end-gate, and locking-rods therefor, of a catch comprising 115 an offset shank forming a shoulder at an intermediate point of its length and fastened at its lower part to said end-gate to have the free end of said shank stand away from the gate, an inclined spring carried by said off- 120 standing free end of the shank, and an operating-rod, for the purpose described, substantially as set forth.

2. The combination with an end-gate, and locking-rods therefor, of an offset angularly- 125 bent fastener-shank attached at its lower end to the end-gate and having its free end arranged away from the gate to expose the shoulder formed by the offset of the shank and enable the locking-rods to rest upon said shoulder, a spring on the free offstanding end of the shank and inclined toward the gate to terminate above the shoulder of the shank, and a headed stem fastened to the spring and

extending through the offstanding end of the shank, substantially as described.

3. An end-gate comprising the back board, the metallic wings having the end edges notched and folded upon themselves and with the flanged side edges which overlap the back board, the perforated bearing-plates fastened over the flanged edges of the wings, the rods to pass through the back and the bearing-
5 plates, and the vertical offset catch-shank fastened to the back board between the bear-

ing-plates and provided at its free end with the spring and with the pull-spindle, substantially as described.

In testimony that I claim the foregoing as 15 my own I have hereto affixed my signature in the presence of two witnesses.

ISAAC CRUZAN.
